CLAIM

I claim the ornamental design for a portable diaper station, as shown and described.

DESCRIPTION

FIG. 1 is a perspective front view of the portable diaper station showing my new design;

FIG. 2 is a front view thereof;

FIG. 3 is a top view thereof;

FIG. 4 is a bottom view thereof;

FIG. 5 is a first side view;

FIG. 6 is a second side view; and,

FIG. 7 is a rear view thereof.

The cube-like feature on the top of the device is an open shute that accesses the main body.
